(57) **CLAIM**

The ornamental design for a portion of a multi-functional connector, as shown and described.

DESCRIPTION

FIG. 1 is a perspective view of a portion of a multi-functional connector according to my new design;

FIG. 2 is a front view of the portion of the multi-functional connector of FIG. 1, the rear view being a mirror image thereof;

FIG. 3 is a right side view of the portion of the multi-functional connector of FIG. 1, the left side view being a mirror image thereof;

FIG. 4 is a top view of the portion of the multi-functional connector of FIG. 1; and,

FIG. 5 is a bottom view of the portion of the multi-functional connector of FIG. 1.

The broken line representation of the remaining portion of the multi-functional connector in FIGS. 1-5 represents environmental structure and is for illustrative purposes only. The broken line representation forms no part of the claimed design.
